(57) **CLAIM**

The ornamental design for a data memory storage drive, as shown.

DESCRIPTION

FIG. 1 is a front view of data memory storage drive;
FIG. 2 is a top view thereof;
FIG. 3 is a bottom view thereof;
FIG. 4 is a left-side view thereof;
FIG. 5 is a right-side view thereof;
FIG. 6 is a perspective view thereof;
FIG. 7 is an exploded front perspective view thereof;
FIG. 8 is a rear perspective view thereof; the cap is shown separately for clarity of illustration; and,
FIG. 9 is a rear view thereof.
